UNITED STATES PATENT OFFICE.

JOHN H. CARTER, OF SUMTER, GEORGIA.

SWINGLETREE.

1,059,829.

Specification of Letters Patent. Patented Apr. 22, 1913.

Application filed November 20, 1912. Serial No. 732,556.

To all whom it may concern:

Be it known that I, JOHN H. CARTER, a citizen of the United States, residing at Sumter, in the county of Sumter and State 5 of Georgia, have invented new and useful Improvements in Swingletrees, of which the following is a specification.

This invention relates to swingletrees, and the object of the invention is to provide a 10 simple, strong and durable construction of swingletree or doubletree which may be inexpensively manufactured of wood and metal, and which is adapted to afford certain substantial advantages, all as fully herein- 15 after described and claimed.

In the accompanying drawing illustrating the invention;—Figure 1 is a plan view of a swingletree constructed in accordance with the invention. Fig. 2 is a section on the line 20 2—2 of Fig. 1. Fig. 3 is a view of a portion of the device on an enlarged scale.

In carrying my invention into practice I provide a swingletree or doubletree consisting of a bar or body portion 1, preferably 25 made of wood, and a metallic reinforcing frame 2. The frame 2 consists preferably of a single piece of scrap iron, comprising longitudinally extending arms 3 and 4, the arm 3 being provided at its ends with right 30 angularly bent portions 5 bearing against the ends of the bar 1 and intersecting the ends of the arm 4, thus forming a loop embracing the bar and reinforcing it in a firm and substantial manner to resist the strains 35 imposed thereon. The ends of the arm 4, and the angularly bent portions 5 at the ends of the arm 3, are bent outward in abutting relation to provide trace hooks 6, which hooks are of spiral form and project a slight 40 distance in advance of the front side of the bar 1 and have their terminals so arranged as to require the rings or eyes upon the ends of the traces to be applied at an angle, so that such rings or eyes, after application, 45 will be securely held against casual displacement.

In practice the ends of the strip of scrap metal of which the reinforcing frame is made preferably overlap along the length of 50 the arm 3 and are welded together, thus form-

ing a substantially single piece structure. Bolts or rivets 7 pass through the ends of the bar 1 and ends of the arms 3 and 4 and terminally connect them, while similar bolts or rivets 8 pass through the bar and arms 55 adjacent to and on opposite sides of the transverse centers thereof and rigidly unite them at these points, thus firmly binding the parts together. A draft ring or eye 9 may be fastened to the swingletree or doubletree, thus constructed by means of the said bolts or rivets 8, or may be welded or otherwise secured to the arm 3 of the reinforcing frame.

From the foregoing description, it will be 65 seen that my invention provides a swingletree or doubletree composed of a body portion of wood, reinforced by a metallic frame in such manner that it is not liable to break, but which, in the event of injury, may be 70 detached by removing the rivets for the substitution of a new bar, the reinforcing frame being practically indestructible. The construction described also obviates the necessity of using rings, bands or clevises and 75 other auxiliary parts, and enables the traces to be securely held and prevented from rattling. The construction of the swingletree or doubletree and arrangement of the trace hooks also permits the draft animal or animals to be placed closer to the vehicle, with 80 resultant advantages.

I claim:—

A swingletree or doubletree comprising a wooden body, a looped metallic frame 85 enclosing the same, said frame consisting of opposed arms bearing against opposite sides of the body, one of said arms having right angularly bent end portions bearing against the ends of the body, the respective ends of 90 the arms being continued outward from the frame in abutting relation and tend to form spiral trace hooks.

In testimony whereof I affix my signature in presence of two witnesses.

JOHN H. CARTER.
